UNITED STATES PATENT OFFICE

2,467,135

CARBON SUPPLY DEVICE FOR WRITING MACHINES

Louis Jensen, Chicago, Ill., assignor to United Autographic Register Co., a corporation of Illinois

Application October 12, 1945, Serial No. 621,950

1 Claim. (Cl. 197—134)

1

This invention relates to an attachment for a typewriting machine, such as a tabulating machine, wherein fresh carbon strips are advanced in interleaved relation with stationery strips led around the platen of a machine.

In writing machines using continuous form stationery, it is common to use "one-time" carbon which is interleaved and is coextensive with the stationery strips.

The primary object of the present invention is to obtain many of the advantages of "one-time" carbon without the waste, and to reduce the problem of disposing of carbon after it has been used in the machine.

Another object of the invention is to provide an attachment for a writing machine wherein a large supply of carbon is stored on rolls in rear of the platen and the carbon rolls are unwound at a much slower rate of travel than the stationery strips, so that fresh carbon is supplied at the printing line of the platen with a minimum of wastage.

Another object of the invention is to provide an automatic control for the unwinding of the carbon strips which will be operated in timed relation to the stationery feeding mechanism, but at a much slower rate of travel.

The invention is illustrated in a preferred embodiment in the accompanying drawings, in which—

Figure 1 is a vertical side elevational view of the attachment with portions of the writing machine shown diagrammatically; and Fig. 2 is a front elevational view of the same.

In the embodiment illustrated, a tabulating machine has a rotary platen 3 around which stationery strips 4 are drawn by a suitable feed mechanism. The stationery strips are shown provided with marginal perforations 5, which are engaged by feeding pins 6 on an endless conveyor 7 whose driving wheel 8 is geared to the platen 3 by gearing indicated diagrammatically at 9. The tabulating machine is provided with typing bars 10, which print a full line at one operation. As shown in Fig. 1, an electric switch 11 is provided with a touch contact 12 and a spring contact 13, so that the circuit is closed automatically each time a typing bar 10 engages the stationery.

The carbon supply device has a main frame 14, having an upright 15 and a guide frame 16, over

2

which the printed forms travel from the platen and then drop into refolded relation in a pack 17. A series of carbon roll shafts 18 are journaled in the uprights 15, so that they may be removed to receive fresh carbon rolls 19. Each of the shafts is shown provided with a bevel gear 20, and these gears engage bevel gears 21 on a driving shaft 22 which is journaled on the frame 14, as indicated at 23. The lower end of the shaft is provided with a worm wheel 24, which is engaged by a worm gear on a shaft 25, provided with a ratchet wheel 26. An arm 27 is provided with a spring pressed pawl 28 to engage the ratchet wheel 26, and is urged downwardly by a spring 29. A solenoid 30 has a plunger 31 connected to the arm 27, and the solenoid is in an electrical circuit with the switch 11, so that each time the switch is closed by a type bar the solenoid draws the arm 27 upwardly and imparts a partial turn to the ratchet 26. This in turn causes the carbon rolls 19 to turn counterclockwise, as viewed in Fig. 1, and permit a small amount of carbon strips 19a to travel forwardly with the stationery around the platen.

Preferably the ratchet wheel permits the carbon strips to advance but a small fraction of an inch at each operation, so that a very small amount of carbon is required to take care of the printing of a substantial length of stationery. It will be understood that the carbon strips are narrower than the lines of marginal perforations in the stationery, so that the carbon is not engaged by the pins 6. The worm carbon advances slowly and may be withdrawn from between the stationery from time to time by the operator, preferably while the stationery is passing over the guide frame 16.

The foregoing detailed description is given for clearness of understanding only, and no unnecessary limitations should be understood therefrom, for some modifications will be obvious to those skilled in the art.

I claim:

In a line by line tabulating machine: a rotary platen and typing bars; an endless belt conveyor mounted above said platen and geared to move therewith, said conveyor having feed pins to engage marginal perforations in stationery strips and draw the stationery strips around said platen; a plurality of carbon rolls in rear of said

platen from which narrow carbon strips may extend forwardly in interleaved relation with said stationery strips, said rolls being geared together; and step-by-step turning means for driving the carbon rolls in slower timed relation to the advancing stationery including a ratchet, a pawl, an actuating solenoid for said pawl, and an electric switch for energizing said solenoid and adapted to be operated by a typing bar.

LOUIS JENSEN.
